UNITED STATES PATENT OFFICE.

LESLIE CARL DUTRO, OF LONG BEACH, CALIFORNIA.

OIL CUP.

Application filed July 26, 1923. Serial No. 653,994.

To all whom it may concern:

Be it known that I, LESLIE CARL DUTRO, a citizen of the United States, and a resident of Long Beach, in the county of Los Angeles and State of California, have invented a new and Improved Oil Cup, of which the following is a full, clear and exact description.

This invention relates to oiling devices 10 for engines either gas, air or steam and has for an object to provide an improved construction which will automatically feed a given quantity of oil during the operation of the engine and will automatically stop 15 the feeding of oil when the engine stops operating.

Another object of the invention is to provide an oil cup for engines wherein the quantity of oil fed into the engine is in 20 proportion to the number of reciprocations in the piston of the engine.

A still further object of the invention is to provide an oil cup which may feed either warm or cold oil and which acts under the 25 compression of the cylinder of the engine so that the feed is positive.

In the accompanying drawing—

The figure is a longitudinal vertical section through part of an engine cylinder and 30 through an oil cup disclosing an embodiment of the invention.

Referring to the accompanying drawing by numerals, 1 indicates the cylinder of an engine of any desired type, as for instance, 35 an internal combustion engine, air or steam engine. Arranged in the engine is a piston 2 which moves back and forth as the engine operates. A tubular member 3 is threaded into the cylinder 1 near the compression end of the cylinder and preferably at the point where the head of the piston stops before said piston changes its direction of travel whereby the end of the passage-way 4 is closed at the beginning of the power 40 stroke but is shortly opened thereafter so that part of the power gaseous matter, as for instance, air, steam or explosive mixture, may enter the passage-way 4 and from thence pass the needle valve 5 so as to be discharged through the tube 6 into the cup 7. Preferably, the outer end of the tubular member 3 is bent upwardly and is provided with a threaded socket for receiving the threaded end 8 of the boss or hub 9 of bottom 50 10, said bottom being connected in any desired manner with the side walls 11 of the cup 7. Preferably, the side walls 11 are of glass so that the level of the oil may be readily observed while the bottom 10 is of metal and the hub 9 projects therefrom and 55 presents a casing for the needle valve 5 and a threaded socket for receiving the threaded lower end of the tube 6. The valve 5 is held in place in the usual manner of needle valves and may be adjusted to permit the discharge of any desired quantity of oil according to the pressure used in the cylinder 1.

The pipe 6 is provided with a number of apertures 12 for the free passageway of oil 70 from the cup 7 into the pipe 6. A suitable cap or covering 15 is connected in any suitable manner to the upper ends of the walls 11, the entire cup 7 being so connected together as to withstand an appreciable pressure.

In operation, when pressure is injected or generated in the pressure chamber 16, it will naturally move the piston 2 on its power stroke and some of the air, gas or explosive 80 matter forming the impelling medium will enter the passage-way 4 and pass upwardly through the pipe 6 into the upper part of the cup 7 so as to provide pressure above the oil in the cup. As soon as the power stroke 85 has been completed and the piston begins to return, the pressure in the upper part of the cup 7 will then force a given quantity of oil into the cylinder. The flow of oil continues until the piston 2 closes the passage-way 4 or until there is an equilibrium 90 between the pressure in the cylinder 1 and in the cup 7. If the engine should stop with the piston 2 uncovering the passage-way 4, oil will flow in until the rarefaction 95 in the cup 7 is such that the pressure in the cylinder stops the flow of the oil, though if there is a pressure in the cylinder 1, this pressure will stop the flow of oil before rarefaction is attained in the cup. It will, 100 therefore, be seen that the oil is injected or fed into the cylinder in proportion to the number of reciprocations of the piston and the pressure used. It will also be noted that the flow of oil will stop substantially 105 at the same time that the engine ceases to operate. It will also be evident that a larger or smaller amount of oil may be caused to flow into the cylinder 1 by adjusting the needle valve 5 manually but when once adjusted only a certain amount 110 will be fed in at each stroke of the piston.

The use of the needle valve 5 is to regulate the amount of gas, air or steam passing through to the upper part of the cup. Naturally, the more that is allowed to pass through, the greater the pressure and the greater the amount of oil fed. It also acts as a friction device which will allow the passage of oil only when the pressure in the top of the cup accumulates and is of sufficient force to feed the oil before another impulse is received. The idea of forcing oil into the cylinder is important in that it helps the rings of the piston to maintain a tight joint. By actual test, it has been found that a cylinder not properly lubricated allows more of an impulse to pass the piston rings than when it is properly lubricated. This is due to the fact that the walls of the cylinder are completely covered with a thin film of oil when properly lubricated. When this film breaks up at any part, the piston rings are held away from the walls of the cylinder a very short distance and thereby this makes an opening through which the pressure from the explosion side rushes. While probably very much of the explosion does not come through, yet there is quite an impulse or pressure formed between the first and second rings. This is varied according to the lubrication, sufficient lubrication allowing very little of the impulse to come through and, consequently, the arrangement of the needle valve 5 and the cup as described, permits a substantially accurate amount of oil to be fed according to the speed of the piston and also other conditions. It will be evident also that the cup will operate efficiently on steam engines as well as air compressors.

In the case of steam engines, the cups are 40 preferably placed just below the throttle and the opening of the valve in the steam chest causes a slight fluctuation in the pressure which can be taken advantage of by regulating the needle valve 5. 45

What I claim is:—

1. An oil cup for lubricating engines, comprising a container formed with a bottom having a boss or hub, said boss or hub having a threaded socket and a restricted 50 passage-way extending from the socket, a needle valve arranged in said hub and adapted to restrict said passage-way according to the position of the valve, a tubular member screwed into said socket extending to near the top of said container, said tubular member having a plurality of apertures arranged therein at different levels, and a member having a restricted passage-way connected with said hub and adapted to 60 connect said cup with an engine cylinder at a point covered by the piston of the engine when starting its power stroke. 55

2. An oil cup for lubricating engines comprising a container having an apertured bottom, a tubular member connected with said bottom so as to discharge directly into the aperture in said bottom, said tubular member extending near the top of said container, said tubular member having apertures arranged at different levels, and a member having a restricted passageway connected with said bottom and adapted to connect said cup with an engine cylinder at a 70 point covered by the piston of the engine 75 when starting its power stroke.

LESLIE CARL DUTRO.
